FIG.2

FIG.3

FIG.4

FIG. 5

FIG. 1 is a perspective view of a canister showing my new design;

FIG. 2 is a perspective view with the cover removed; FIG. 3 is a perspective view with the canister resting on one side;

FIG. 4 is a perspective view looking into the canister and with the cover in exploded relationship; and

FIG. 5 is a perspective view of the canister taken from the side opposite that shown in FIG. 1.

This is a continuation-in-part of my earlier design application Ser. No. 18,532 of Aug. 4, 1969, now abandoned.

I claim:

The ornamental design for a canister, as shown and described.
